(57) **CLAIM**

The ornamental design for high adjustment device for refrigerator door, as shown and described.

DESCRIPTION

FIG. 1 is a front perspective view of a high adjustment device for refrigerator door showing our new design;

FIG. 2 is a back perspective view thereof;

FIG. 3 is a front view thereof;

FIG. 4 is a top view thereof;

FIG. 5 is a bottom view thereof;

FIG. 6 is a side view thereof; and,

FIG. 7 is another side view thereof.
